UNITED STATES PATENT OFFICE

ALFRED H. ENDORF, OF WHEATLAND, IOWA

POWER SCRAPING MACHINE

Application filed September 14, 1928. Serial No. 306,077.

My invention has reference to a scraping machine, and is more specially designed for use in removing the accumulation of foreign matter on butcher's blocks. It is usual to 5 clean the blocks at the close of each day's business, and this is done by scraping the surface of the block with a large knife or cleaver. This is not only a very laborious operation, but it results in the surface of the block being 10 worn unevenly, so that in time it has to be reshaped, by cutting off a portion of the block.

By the use of the present invention it is possible to thoroughly clean the surface of 15 the block without any abrading effect thereon. The machine is power driven, and the work can be performed quickly, and with a minimum of labor. The accumulation of matter which is removed from the block is 20 collected in the machine in such a manner that it can be easily removed therefrom.

The particular construction, arrangement, and manner of operation of the machine will 25 more fully appear from the following specification, reference being had to the accompanying drawings, in which:—

Fig. 1 shows the invention in side elevation.

Fig. 2 is a longitudinal section through 30 the same.

Fig. 3 is a cross-section on the broken line 3—3 of Fig. 1.

Fig. 4 is an enlarged detail of the scraper wheel.

35 The reference number 1 indicates a box or casing, provided with a top 2, and supported on rollers 3, extending across the inner width of the box. At one end of the box is a hinged door 4, and the opposite end is open, except 40 as it is closed by a pan 5, slideable in the box, and provided with a handle 6. The pan is fitted with a floor 7, extending a part of the length of the box, and the upper part of the pan is projected to the opposite end of the 45 box from the end in which the pan is inserted, as at 8. By means of handles 9 fixed to the top 2 the machine can be run back and forth on a butcher's block or other surface.

In the sides of the box 1 are oppositely disposed 50 openings 11, in which are vertically

movable boxes 12, in which are rotatably mounted the ends of a shaft 14. Curved scrapers 14 are secured in sets or pairs in the central squared portion 16 of said shaft, the ends of said scrapers being provided with 55 straight edges 15. The pairs of scrapers are preferably formed integrally, the squared portion of the shaft being formed of four similar strips connected with each other, and between which the scrapers are secured. The 60 scrapers are also formed of spring metal, and are disposed so that the central portion of one pair is at right angles with that of the next adjacent pair.

On one end of the shaft 13 is a pulley 17, 65 driven from an electric motor 18 mounted on the box 1, by means of a belt 19 passing round the pulley 17 and round a pulley 20 on the end of the drive-shaft of the motor, and also round an idler pulley 21 supported on the 70 side of the box. Movement is imparted to the shaft 13 to cause the scrapers 14 to rotate in the direction indicated by the arrows, the scrapers being held at a height suitable for 75 cleaning the surface of the block. The height of the scrapers is capable of adjustment, springs 23 being interposed between the lower ends of the openings 11 and the boxes 12, which tend to move said boxes upwardly. Above the box 1 is a cross-bar 24, in the ends 80 of which is fixed a pair of rods 25, the lower ends of which are provided with plates 26 which bear against the upper ends of the boxes 12. Centrally of the bar 24 is a thumb-screw 27, rotatably mounted in an arch-plate 85 28, fixed to the top of the box 1, the ends of said arch-plate being perforated to permit free movement of the rods 25 therein. Between the ends of the cross-bar 24 and arch-plate 28 are coiled springs 29 which hold the 90 cross-bar and rods 25 yieldably in a raised position. By turning the screw 27 in the proper direction the bar 24 is moved downwardly, also forcing the boxes 12 downwardly, and bringing the scrapers 14 into closer 95 proximity to the object upon which it is being used. By a reverse movement the boxes 12 are permitted to rise again, and the scrapers are carried upward therewith.

To maintain the ends of the shaft 13 at 100

uniform height coiled springs 30 are positioned in spaces 31 in the side walls of the box 1, the lower ends of said springs bearing against the plates 26.

5 In operation, the machine is moved back and forth over the block, with the motor in operation, and the scrapers in a position to clean the surface of the block, without any effect upon the block itself. The material that
10 is scraped from the block is thrown rearwardly and upwardly into the pan 5, from which it can be removed by taking the pan out of the machine. By opening the door 4 it is possible to get at the scrapers themselves in
15 order to give attention thereto.

In order to work effectively it is essential that the blades 14 shall have a considerable width in proportion to their length, the width thereof in a machine of moderate size being
20 approximately two inches. This does better work in removing the accumulation from the block, and with less danger of injury to the block itself. The spring action of the scrapers also permits a flexible contact with the
25 block, if any, without any abrasive action thereon.

As the machine is shoved back and forth its position is frequently changed until the whole surface of the block has been cleaned.
30 The two rear rollers support the casing to such an extent that the forward roller can be run off the edge of the block without interrupting the operation of the machine.

What I claim, and desire to secure by Letters Patent is:

A device of the class described, comprising a rollingly mounted casing open at the bottom, a container removably held in said casing, partially closing the bottom thereof and
40 projected at its upper part from end to end of the casing, a scraper rotatably mounted above the open part of said casing, and formed of curved spring blades, means for adjustment of said scraper vertically, and
45 means for rotating said scraper.

In testimony whereof I affix my signature.

ALFRED H. ENDORF.
